METHOD OF LOADING TEXTILE MATERIAL

Filed June 19, 1928

Inventor:

Rene Clavel
by Luc Vaniglia, Attorney.

UNITED STATES PATENT OFFICE

RENÉ CLAVEL, OF BASEL, SWITZERLAND

METHOD OF LOADING TEXTILE MATERIAL

Application filed June 19, 1928, Serial No. 286,574, and in Switzerland August 23, 1927.

The present invention relates to a method for loading textile material particularly material containing silk in the form of hanks or runs.

5 The invention includes the provision of a single centrifuge common to a number of supply tanks and fluid circuits, and fluid supply and discharge pipes for the various loading liquids which are provided with regulating devices to allow of introducing or running off a plurality of loading liquids separately or together.

10 For this purpose both the fluid supply pipe and also the discharge pipe of the centrifuge are provided with a multi-way cock in order to allow establishing a connection with any one of the supply or connecting vessels for the loading agent as desired.

15 The collecting vessels themselves are connected with lifting mechanisms for example pumps or pulsometers which are in connection with the supply containers, so that the liquid used at any time for loading the goods circulates from the supply vessel into the centrifuge, from there into the collecting vessel and back to the supply vessel.

20 The loading of textile materials containing silk has not hitherto been possible in such a continuous apparatus, as numerous washings, acidifications or neutralizations of the material treated have been necessary between the individual baths.

25 The application of the device according to the present invention has been rendered possible by the discovery that the objectionable washings, acidifications or neutralizations between the separate baths can be eliminated, so long as care is taken that the metallic salt, particularly stannic chloride, acts on the silk only in the presence of acid or acid salt. These acid substances or mixtures themselves act on the silk containing textile material separately or along with the stannic chloride bath. Continuous, simple, and, from the economical point of view, profitable, loading of the material is rendered possible for the first time by this process.

30 One form of construction of the invention is shown in the accompanying drawing in which:—

Figure 1 is a front elevation of the plant and

Figure 2 is a side elevation of the same.

A dependent centrifuge 4 with base discharge is provided below three vessels 1, 2 and 3. The vessel 1 contains the acid, for example formic acid. The vessel 2 the metal loading bath, for example the stannic chloride solution, and the vessel 3 the fixing solution, for example a mono-sodium dihydrogen phosphate solution.

35 A common pipe 5 is connected to the three containers, the supply to which can be automatically regulated by cocks 6a, 6, and 6b. The pipe 5 discharges its contents through a pipe 7 into the centrifuge 4. A discharge pipe 8 from the centrifuge 4 is provided with a three-way cock 9, which allows the liquid from the bath in use at any time to be led away through any of the separate pipes 10, 11, and 12 into collecting vessels 13, 14 and 15.

40 The solutions pass from the collecting vessels into separate pulsometers or pumps 16, 17, 18, which are connected respectively by pipes 19, 20 and 21 with the corresponding supply vessels 1, 2 and 3.

45 The material is first introduced into the centrifuge 4 and acid is then added from the vessel 1 through the pipe 5, three-way cock 6, and inlet pipe 7. After a predetermined time, during which the centrifuge is in operation, the acid is led through the pipe 8, three-way cock 9 and pipe 10 into the collecting vessel 13 and is returned by the latter through the pulsometer 16 and the pipe 19 to the supply vessel 1. The silk which has been well centrifuged is then treated with the stannic chloride solution in the same manner as with the acid and then, after it has again been well centrifuged, is treated with the mono-sodium dihydrogen phosphate solution. Fourway cocks can also be used instead of three-way cocks if it is desired to employ, in addition, treatment with sodium silicate solution similarly as with the remaining loading agents.

50 The vessels, pipes and centrifuges used, are provided with acid resistant linings, for example hard or vulcanized rubber.

55 The loaded material is removed from the

centrifuge on completion of the loading process and thoroughly washed in shallow vats or other washing apparatus.

I claim:

- 5 1. A method of loading textile material consisting in treating the textile material successively with an acid, a metal loading solution and a fixing solution consecutively in a single centrifuge without removal 10 of the material from said centrifuge during the consecutive steps of the process and without washing the material treated with the metal loading solution.
- 15 2. A method of loading textile material consisting of silk of any kind consisting in treating the silk successively with an acid, a metal loading solution and a fixing solution consecutively in a single centrifuge without removal of the material from said 20 centrifuge during the consecutive steps of the process and without washing the silk treated with the metal loading solution.

In testimony whereof I affix my signature.

RENE CLAVEL.
